UNITED STATES PATENT OFFICE.

HARRY THOMPSON, OF BAILLIEBORO, SOUTH MONAGHAN, ONTARIO, CANADA.

TELEPHONE.

1,177,455.

Specification of Letters Patent. Patented Mar. 28, 1916.

Application filed July 18, 1914. Serial No. 851,732.

To all whom it may concern:

Be it known that I, HARRY THOMPSON, a subject of the King of Great Britain, residing at Baillieboro, South Monaghan, in the Province of Ontario and Dominion of Canada, have invented certain new and useful Improvements in Telephones; and I do hereby declare the following to be a full, clear, and exact description of the invention, such as will enable others skilled in the art to which it appertains to make and use the same.

This invention relates to telephones, and more particularly to an attachment for what is commonly known as party line telephones, such as are used in rural districts, wherein all of the telephones are operatively connected, so that the parties on each and every station may listen to the conversation between any two stations should they so desire.

The primary object of this invention is the provision of a signaling attachment for connection with the various telephones, which signaling attachment will immediately, upon the moving of the telephone receiver from the supporting hook, sound the designating signal of the telephone from which the receiver is removed, thereby acquainting the parties who are talking upon the line that such and such a person has taken down their receiver for the purpose of listening to the conversation.

A further object of the invention is to provide a means by which the downward movement of the signaling plate may be retarded, thereby insuring the proper timing of the signals.

Still another object of the invention is to provide a device by means of which the forcing of the signaling plate is prevented.

A further and more specific object of the invention is to provide a device to prevent a person from operating the telephone ringer until after the signal has been given.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters of reference

designate like or corresponding parts throughout the several views, and in which:

Figure 1 is a sectional view through the ordinary type of party telephone as specified showing the improved attachment applied thereto. Fig. 2 is a fragmentary view of a part of the signaling attachment for the telephone. Fig. 3 is a cross sectional view on line 3—3 of Fig. 1. Fig. 4 is a detail view in elevation showing a part of the signaling mechanism in an operated position. Fig. 5 is a fragmentary view of a part of the construction of the invention showing the telephone locking member, and Fig. 6 is a detail view of the pivoted plate and support therefor.

Referring more particularly to the drawings, 1 designates a telephone of the type which is commonly used on party lines in rural districts, which telephone embodies the bell-ringing lever 2, the receiver 3, the receiver supporting hook 4, the gear 5 and pinions 6, for operating the telephone signaling mechanism, and other features of construction such as are commonly found in telephones of this nature.

The telephone has a leaf spring 7, which leaf spring engages the lower surface of the receiver supporting hook 4, and it is normally held under tension by the receiver 3 when the same is mounted upon the hook 4, so that immediately upon the removal of the receiver from the hook the spring 7 will force the hook upwardly, as is ordinary in the construction of telephones of this nature.

The casing 8 in which the telephone is mounted, has an auxiliary casing 9, mounted thereupon, which auxiliary casing has the signaling mechanism, which will be herein-after more fully described, mounted therein.

The receiver supporting hook 4 has a bar 10 secured to the end 11 thereof, which projects out of the telephone casing 8 and the bar 10 is pivotally connected as at 12 to a rocker arm 14, which is pivotally mounted on a pin 15. The pin 15 is supported by a partition 16, which partition is mounted within the casing 9. The rock arm 14 is of a novel form having an angular horizontal flange 17 formed along its lower edge at the rear end thereof. This flange 17 is adapted to form a rest to support the plate 18 which is pivotally mounted within the

casing 9 and it will be seen that when the rock arm 14 moves into the position shown in Fig. 4 the plate 18 will be free to move downwardly under the influence of its own weight. It will be noted that the manual movement of the rock arm 14 will have no effect in forcing the plate 18 to move downwardly at an increased speed and it will thus be seen that the dash pot which will be more fully hereinafter described will insure the proper timing of the signals. The plate 18 has a bar 19 connected thereto, which bar is in turn connected to the piston rod 20 of a dash pot 21. The dash pot 21 is supported upon the rear face of the partition 16 by a strap 22, which extends about the dash pot and binds the same in engagement with the surface of the partition 16. The piston (not shown) of the dash pot 21 retards the downward pivotal movement of the plate 18, so that the timing of the signals will be uniform throughout the operation of the device.

The forward edge 23 of the plate 18 is arcuate and provided with a plurality of notches or indentations 24. The notches or indentations 24 are spaced along the length of the arcuate edge 23 of the plate 18, so that the distance between the notches adjacent each other, will be such that they represent the number of rings by which the telephone to which the lever 10 is connected is designated. For example: in case the telephone 1 is known by two short, two long and a short, the notches 24 will be spaced so as to form two short spaces, adjacent each other, two long spaces adjacent each other, and a short space positioned upon the opposite end of the side 23 from the first two short spaces, or as is clearly shown in the drawings.

The partition 16 has pivotally mounted thereupon two levers 25 and 26, the levers being pivoted so that the terminals of their longer ends will engage upon rocking movement of the lever 25. The lever 25 has its forward short end 27 bent upwardly or substantially at right angles to the lever and the upwardly bent end 27 is provided for engagement with the arcuate marginal edge 23 of the pivoted plate 18.

The levers 25 and 26 are pivotally mounted upon pins 28 and 29 respectively, which pins have communication through flexible electric conductors 30 with the opposite poles of an annunciator 31 through a battery circuit so that when the terminals of the long ends of the levers are in engagement with each other the annunciator 31 will be operated sounding a signal.

The casing 8 has a bracket 33 mounted therein in which bracket is slidably seated a rod 34. The rod 34 extends vertically through the bracket 33 and into the interior 65 of the auxiliary casing 9, being guided in

its movement within the casing 9 by a strap 35, which strap is secured to the partition 16, or the casing 9 as desired.

The rod 34 has an arm 36 secured thereto adjacent its upper end and movable and adjustable by means of a thumb screw 36', which rod is provided for engagement by one end of the lever 37. The lever 37 is pivotally mounted within the casing 9 and extends transversely thereacross, being held 75 in an upward opposite position by an elastic supporting member which is secured to the partition 16 in any suitable manner.

Suitable stops 39 and 40 are carried by the partition 16 for limiting the movement 80 of the lever 37. An arm 41 which has its lower terminal end bent so as to provide for abutting engagement with the upper surface of the lever 37, is securely attached to the pivoted plate 18, so that upon downward movement of the pivotal plate, the arm 41 will engage the lever 37, and move the end which is positioned upon the opposite side of the pivotal point of the lever from the arm 36 downwardly, forcing the 90 end which is adjacent the arm 36 upwardly and moving the rod 34 upwardly within its bearings and out of engagement with the peripheral teeth of the gear 5, which is mounted in the telephone box 8 as has been 95 heretofore described, thereby permitting of the operating of the gear and the telephone 1.

In the operation of the improved signaling attachment for telephones; when the receiver 3 is removed from the receiver hook 4, the bar 10 will be operated by the upward movement of the receiver hook which will in turn operate the rock arm 14 causing the flange 17 formed thereon to move out of a 105 supporting position with relation to the pivotal plate 18, and permitting the plate to move downwardly within the auxiliary casing 9. Upon the downward movement of the pivotal plate 18, the marginal edge 23 110 thereof will engage the upturned end 27 of the lever 25, and upon the engagement of the arcuate edge 23 with the end 27 of the lever 25, the lever 25 will be operated upon its pivotal point and moved so that it will 115 engage the lever 26, closing a circuit between the two poles of the annunciator 31. The notches 24 which are formed in the arcuate edge 23 of the plate 18 will release the lever 25 and cause the same to move out of engagement with the lever 26, thereby breaking the circuit, so that the entire movement of the plate 18 downwardly will sound the signal which designates the telephone to which the attachment is connected.

The plate 18 in reaching the lower terminus of its pivotal movement, which is regulated by the operation of the piston 20 within the cylinder 21, will cause the angled end of the arm 41 to engage the lever 37, 130

forcing the same downwardly and operating the rod 34 in a vertical manner so as to permit the rotation of the gear 5 and the operation of the telephone in the ordinary manner.

From the foregoing description taken in connection with the accompanying drawings the advantages of the construction and of the method of operation of the improved telephone attachment will be readily apparent to those skilled in the art to which this invention appertains and while in the foregoing description, the principle of the operation of this invention has been described together with various features of construction, it is to be understood that certain minor features of construction, combination and arrangement of parts may be altered, to suit practical conditions provided such alterations are comprehended within the scope of what is claimed.

What is claimed is:—

1. The combination with a telephone having a receiver hook, and a receiver on said hook, of a signaling means comprising a casing, a signal plate mounted within the casing, a rocker arm mounted on the same pivot with the signal plate, means connecting the rocker arm with the receiver hook whereby upon removing the receiver from the receiver hook, the rocker arm will be moved upwardly, thereby allowing the sig-

nal plate to move downwardly means to retard the movement of the signal plate to insure the proper timing of the signal, 35 means to prevent the ringing mechanism of the telephone from being operated during the movement of the signal arm, thereby avoiding the confusing of signals, and means to allow the ringer to be operated 40 after the signal has been given.

2. In combination with a telephone having a casing, a receiver hook pivoted within the casing and a receiver on the hook of a second casing, a rocker arm pivoted in the second casing, a rod connecting the outer end of the rocker arm with the free end of the receiver hook, a signal plate pivoted on the pivot of the rocker arm, a flange on the rocker arm normally holding the signal plate elevated, signaling means actuated upon the downward movement of the signal plate, means to retard the downward movement of the signal plate, to insure the proper timing of the signal, a ringer for the telephone, and a stop adapted to hold the ringer against movement until the signal has been given over the line. 55

In testimony whereof I affix my signature in presence of two witnesses.

HARRY THOMPSON.
